PUMPING APPARATUS

Lester L. Clark, Akron, Ohio

Application May 5, 1938, Serial No. 206,197

4 Claims. (Cl. 103—235)

This invention relates to improvements in automatic apparatus for elevating a liquid from an enclosed space by alternately introducing to such space, air or gas under pressure to force liquid therefrom, then refilling the space by subjecting the same to suction.

Other objects are to provide improved means for forcing water from a well, tank or other enclosed space and to provide means for regulating the alternate application of pressure and suction to such space whereby a considerable part of the air or gas under pressure employed in forcing the liquid from the space can be reused with the expenditure of a small amount of energy.

15 A particular object is to provide a pumping apparatus of the character above indicated and to provide simple, efficient timing means therefor which will automatically operate by the alternate pressure and suction employed in the pumping operation.

The above and other obvious objects are accomplished and additional ends are attained by the novel construction, combination and arrangement of parts hereinafter described with 25 reference to the accompanying drawings in which there is shown an illustrative embodiment of the invention, it being understood that the invention is not confined to the particular form shown and that the same may be applied in various ways 30 to various pumping operations and that changes and modifications may be made which come within the scope of the appended claims.

In the drawings:

Figure 1 is a side elevational view of a pumping apparatus constructed in accordance with this invention, the same being somewhat diagrammatic in character with parts shown in vertical section.

Figure 2 is a central, cross sectional view of one 40 of the valves used in reducing the invention to practice.

Figure 3 is a like view of same showing the valve operated to a different position.

Figure 4 is a central, vertical, sectional view of 45 a check valve employed in my improved apparatus.

Figure 5 is a central, vertical, sectional view showing a suction operated valve which may be employed in reducing the invention to practice.

50 Figure 6 is an elevational view of a modified form of the invention, the same being somewhat diagrammatic in character with parts shown in cross section to more clearly illustrate the invention.

55 Figure 7 is a central, vertical, sectional view of

one form of valve which may be employed in carrying out the invention, the same being shown with the stem portion broken away and the valve shown mounted in a pipe line with the end portions of the pipe shown.

Proceeding now to a detailed description of the invention with reference to the particular adaptation thereof disclosed in the drawings, the numeral 5 denotes an air compressor which may be of any desired construction and which is 10 provided with an inlet pipe 6 and an outlet pipe 7. The outlet pipe 7 is operatively connected to a pressure tank 8. A suitable valve 9 is operatively interposed in the pipe 6 and is operable to regulate the passage of air or gas therethrough. 15 A regulatable check valve 10 is also interposed in the pipe 6 for a purpose hereinafter described. The outlet pipe 7 is provided with a suitable valve 11 operable to regulate the flow of air to the tank 8. The tank 8 is provided with a suitable safety valve 12.

The numeral 13 denotes a pipe which leads from the tank 8 and is operatively connected to a three-way valve 14 as shown in Figures 3 and 2. The pipe 6 is connected to the valve 14 and is 25 disposed at a right angle to the adjacent portion of the pipe 13. A pipe 15 is also connected to a valve 14 as shown in Figures 2 and 3. The valve 14 is operated to operatively connect the pipe 15 with the pipe 13 or to connect the pipe 15 with 30 the pipe 6.

The numeral 17 denotes a well casing and the numeral 18 a tube which is closed at the upper end thereof with a lid 19 which is suitably secured thereto. The lower end of the tube 18 is 35 provided with a suitable inlet valve 20 which automatically operates to admit fluid thereto, but checks the flow of fluid therefrom. The pipe 15 is operatively connected to the upper end portion of the tube 18. The delivery pipe 21 is positioned through the lid 19 and projects downwardly in the tube 18 to a point adjacent the bottom thereof; suitable packing 22 being employed to seal the opening through which the pipe 21 projects. The pipe 21 is provided at 40 45 the bottom thereof with a check valve 23 which will admit water or other liquid to the pipe but check the flow of the same therefrom.

A horizontal tube 25 leads from the vertical portion of the pipe 13 and a cylinder 26 is operatively secured thereto. The cylinder 26 is provided with a piston 27 and a piston rod 28 projects outwardly from the outwardly presented end of the cylinder 26. The cylinder 26 is provided at the bottom thereof with suitable lugs 29 50 55

and the piston rod 28 is provided adjacent the other end thereof with a cross arm 30 having a spring 31 secured to each end thereof with the other end of each spring secured to one of the 5 lugs 29.

5 A suitable valve 32 is operatively interposed in the line 13 between the tank 8 and the pipe 25 to regulate the flow of air through the pipe 13. A lever 33 is fulcrumed to a suitable standard 34 and projects horizontally therefrom with the 10 end portion thereof positioned below the cylinder 26. The lever 33 is provided adjacent the free end thereof with a weight 35 which is adjustably secured thereto. The valve 14 is provided 15 with an operating arm 36 and a pitman 37 is pivotally secured to the arm 36 and the lever 33 as shown in Figure 1.

The numeral 38 denotes a trigger member which is hingedly secured to a standard 40 as at 20 39 and extends upwardly with the upper portion thereof in the path of movement of the piston rod 28. A spring 41 yieldably holds the member 38 with the upper portion thereof in contact with the outwardly projecting end of the piston rod 25 28. The member 38 is provided with two stops 42 and 43. The stop 42 is positioned to engage the end of the lever 33 to support the same in the 30 position shown in Figure 1. The stop 43 is relatively wider than the stop 42 and is positioned below the stop 42 to limit the downward movement of the lever 33 when it is released from the stop 42.

When the lever 33 is in the position shown in Figure 1, the valve 14 is held in the position 35 shown in Figure 2 and when the lever 33 is moved downwardly to the stop 43 the valve 14 is in the position shown in Figure 3.

The line 15 is provided with a by-pass line 45 each end of which is connected by suitable fittings to the line 15. The line 45 is provided 40 intermediately thereof with a T-coupling in which is mounted a pipe 46 which projects upwardly therefrom approximately in the plane of movement of the lever 33. A hollow cylinder 47 is operatively mounted on the pipe 46 and a piston 48 is mounted therein. A piston rod 49 projects upwardly from the piston 48 through the upper wall of the cylinder 47. The upper end 45 of the piston rod 49 is provided with a fork 50 in which is received the lever 33. The cylinder 48 is provided with base lugs 51 and the rod 49 with a cross arm 52. The numeral 53 denotes coil springs one of which is secured between each 55 end of the cross arm and one of the lugs 51 whereby the piston will be normally urged by said springs 53 to a downward position in the cylinder 47.

The by-pass line 45 is provided on one side of the pipe 46 with a valve 54 which may be operated to regulate the flow of air from the line 15 to the cylinder 47. The line 45 is also provided on the other side of the pipe 46 with a valve 55.

The valve 55 is provided with a valve seat 56 for receiving the valve head 57. The valve head 57 is mounted on the stem 58 which projects upwardly from the valve 55. An upward movement of the stem 58 opens the valve 55 while a downward movement thereof brings the valve head 57 in contact with the seat 56 to close the 70 valve.

The numeral 59 denotes a washer which is positioned on the stem 58 and which is adjustably supported thereon by the nut 60 which is threaded on said stem. The numeral 61 denotes a coil 75 spring which is positioned on the stem 58 and is

supported by the washer 59. A second washer 62 is positioned on the stem 58 and rests on the upper end of the spring 61. A suitable nut 63 is threaded on the upper end portion of the stem 58. The arm 64 is pivotally secured to the lever 5 33 so as to depend therefrom. The lower end of the arm 64 terminates in a horizontal portion 65 which is provided with an aperture 66 in which is received the upper end portion of the stem 58 with the horizontal portion 65 positioned between the nut 63 and the washer 62. 10

While the vacuum operated valve 10 may be of any desired construction, in Figure 5 I have shown one form of valve which may be used for the purpose herein described and which consists of a tube 10a having an interiorly threaded cap 10b operatively positioned thereon. The cap 10b is provided on the upper side thereof with a boss 10c. The boss 10c is provided with a threaded bore which terminates at the lower end 20 thereof in a valve seat 10d. A coil spring 10e is positioned within the cap 10b to yieldably hold a ball 10f in said seat. A suitable screw 10g is mounted in the bore in the boss 10c. The screw 10g is provided with a longitudinally projecting 25 slot which is relatively wide at the lower end of the screw, and which has side walls which converge adjacent the upper end of the screw whereby the screw 10g may be operated in the boss 10c to regulate the amount of air which can pass 30 through the valve.

To start the apparatus in operation, the valve 32 is closed and the valve 9 opened. The valve 10 in the line 6 is regulated to readily admit air thereto and the lever 33 is positioned as shown 35 in Figure 1 and the compressor 5 is operated to fill the tank 8 with air at a desired pressure. The valve 9 is then regulated and the valve 32 opened to admit pressure from the tank to the line 13. The air flows from the line 13 through the pipe 40 25 to the cylinder 26 and forces the piston 27 outwardly in said cylinder. As the piston is thus forced outwardly, the piston rod 28 engages the trigger member 38 and moves the stop 42 from beneath the end of the lever 33. The lever 33 is 45 carried downwardly by the weight 35 to the stop 43 and moves the valve 14 to the position shown in Figure 3, thus connecting the pipe 13 with the pipe 15 through which air flows to the tube 18 and forces water from the tube 18 upwardly into the 50 pipe 21. It will be seen that with the downward movement of the lever 33, the horizontal portion 65 of the depending arm 64 will rest on the spring 61 and hold the valve 57 in a closed position. 55

The valve 54 has been previously regulated to slowly admit air therethrough and air enters the cylinder 47 and slowly raises the piston 48. The fork 50 engages the lever 33 and moves the same upwardly until the depending arm 64 engages 60 the nut 63 and opens the valve 57 whereupon air rushes from the pipe 15 through the valve 55 to the cylinder 47 and instantly raises the lever 33 to its initial position. The springs 31 on the cylinder 26 have sufficient strength to return the 65 piston 27 to its initial position against the reduced pressure which results from the air flowing into the cavity of the tube 18 thus permitting the spring 41 to force the member 38 to its initial position and causing the lever 33 to be engaged 70 by the stop 42. As this movement operates the valve 14 to the position shown in Figure 2, the compressed air within the tube 18 is drawn into the air compressor 5 and forced into the tank 8. As soon as the air in the tube 18 and the pipe 75

15 has been pumped into the tank 8 the compressor 5 exerts a suction in the tube 18 which draws water from the casing 17 upwardly into the tube 18.

5 The suction in the line 15 also draws the piston 48 downwardly in the cylinder 47. As the compressor continues to operate, additional air is drawn through the valve 10 until the original pressure within the tank 8 has been replaced.

10 This again causes the piston 27 to automatically operate the lever 33 and the valve 14, thus providing means for alternately subjecting the tube 18 to a partial vacuum and to air under pressure for the purpose of forcing water therefrom. The

15 valves 9, 11, 32 and 54 may be regulated to time the periods of operation and the valves 10 may be operated to regulate the amount of suction to which the interior of the pipe 18 is to be subjected.

20 In Figure 6 there is illustrated an adaptation of the invention in which a pipe line 65 is connected to the tank 12 in the same manner as the pipe 13. The pipe line 65 is operatively connected by a T-coupling to a pipe 66 which leads to the tube 18 in the same manner as the pipe 15. A pipe line 68 leads from the T-coupling 67 and is operatively connected to the inlet end of the compressor 5 in the same manner as the pipe 6. A pipe 70 projects horizontally from the line 30 65 and a hollow cylinder 71 having a closed end is slidably mounted on the pipe 70; suitable packing 72 being employed to seal the open end of the cylinder 71.

The horizontal portion 65a of the pipe line 35 65 is provided with a valve 73 which includes a valve head 73a having a valve rod 74 which depends therefrom and which is normally held in a closed position by the spring 74a as shown in Figure 7. The spring 74a yieldably holds the 40 valve 73a in a closed position and the valve is opened by a downward movement of the rod 74. The rod 74 is provided on the lower end thereof with a loop 75 through which extends a horizontal lever 76 which is fulcrumed to a suitable 45 post 77 or other supporting structure by a hinge member 78 for a vertical swinging movement thereon.

The lever 76 is provided adjacent the free end thereof with a weight 79 which is adjustably secured thereto and which normally moves the 50 lever 76 to a downward position.

The numeral 80 denotes a post or other support which is provided on the side presented toward the lever 76 with a trigger member 81 55 which extends upwardly in spaced relation to the post 80 and is hinged thereto as at 82 for a limited swinging movement in the plane of movement of the lever 76. The trigger member 81 extends upwardly in spaced relation to the post 60 80 and is provided with a step 85 which is adapted to engage the end portion of the lever 76 when the lever is in a raised position. A coil spring 86 yieldably holds the trigger member 81 in an outward position and the trigger member 81 extends upwardly beyond the cylinder 71.

A lever 87 is fulcrumed to a suitable bracket 88 and depends therefrom in the path of the cylinder 71 which engages the lever 87 at a point adjacent the fulcrumed end thereof. The free 70 end of the short lever 87 engages the upper portion of the trigger member 81 whereby a relatively short outward movement of the cylinder 71 will cause a substantially greater movement of the member 81.

75 The numeral 90 denotes a by-pass line which

is connected by a T-coupling 91 and 92 to the line 68. A hollow cylinder 94 is operatively connected to the line 90 and projects upwardly therefrom. A piston 95 is mounted in the cylinder 94 with a piston rod 96 projecting upwardly beyond the end of the cylinder. The piston rod 96 is provided with an upwardly presented fork 97 which embraces the lever 76.

The numeral 98 denotes an accelerator tank which may be interposed in the line 90 for a 10 purpose hereinafter described. The line 90 is provided on one side of the cylinder 94 with a handle operated valve 93 which is ordinarily set to slowly admit air to the cylinder 94. The bypass 90 is provided on the other side of the cylinder 94 with a valve 99, similar to the valve 73 15 and which is normally closed.

The valve 99 is provided with a stem 100 which passes through an opening in the horizontal position 102 of the arm 101 which is pivotally secured to the lever 76 at a point adjacent the fulcrumed end thereof. The nut 100a is threaded on the stem 100 whereby it may be adjustably operated thereon to engage the horizontal portion 102 so that the valve 99 is opened by a 25 partial upward movement of the lever 76.

The line 68 is also provided with a valve 104 which is similar to the valves 73 and 99 and which is provided with an upwardly presented stem 103 having a nut 106 which engages the 30 horizontal portion 107 of an arm 108 which depends from the lever 76 whereby the valve 104 is normally closed but is opened when the lever 76 is in a raised position.

The numeral 109 denotes spring operated inlet 35 valves which are similar to the valves 10 and serve the same purpose. Each inlet valve 109 is provided with a stem 110 in which is mounted a coil spring 111 and a nut 112 is threaded on the end of the stem 110 whereby it may be operated to compress the spring 111 and regulate the operation of said valve. A valve 113 is interposed in the line 65 and serves the same purpose as the valve 32.

The cylinder 71 is provided with ears 114 and 45 the coupling 115 in the line 70 with ears 116 and bolts 117 are mounted in suitable apertures in said ears with a spring 118 compressed between each ear 116 and a nut 119 which is threaded on the end of each bolt 117. The springs 118 serve the 50 same purpose as the springs 31.

In using the adaptation of the invention shown in Figure 6, the valve 113 is operated to regulate the flow of fluid from the tank 8 to the line 65. As the valve 73 is closed, the fluid pressure 55 forces the cylinder 71 outwardly against the lever 87 which in turn moves the trigger member 81. This moves the step 85 from beneath the end of the lever 76 whereupon the weight 79 moves the lever downwardly to the stop 120 as shown 60 by the dotted lines in Figure 6.

The downward movement of the lever 76 opens the valve 73 and closes the valves 99 and 104 and air under pressure flows through the line 65 and 66 to the tube 18. The pressure in the 65 pipe 70 is thus released and the springs 118 return the cylinder 71 to its normal position. Air thus admitted by the pipe 66 forces the water downwardly in the tube 18 and discharges it through the pipe 21. Air also flows through the 70 by-pass line 90 and is slowly admitted through the valve 93 to the cylinder 94 thus slowly raising the piston 95. When the piston is raised by the lever 76 a predetermined distance, the arm 101 lifts the stem 100 and opens the valve 99 75

thus suddenly admitting the full force of the pressure to the by-pass 90 and quickly moving the lever 76 upwardly against the stop 121 where it is engaged by the step 85 in the trigger member 81. This movement closes the valve 73 and opens the valve 104 whereby air under pressure in the tube 18 is admitted through the pipe 68 to the intake end of the compressor 5. The compressor easily pumps the air under pressure from the tube 18 and continues to operate until a partial vacuum is created in the tube 18 which raises the water in said tube. When the suction within the tube 18 has reached a predetermined point, the valve 109 operates to admit air to the compressor 5 whereby air lost during each operation is automatically replenished. The partial vacuum also draws the piston 95 downwardly in the cylinder 94. When the pressure in the tank 8 becomes sufficient to overcome the springs 118 the cylinder 71 moves outwardly and the operation above described is repeated.

It will thus be seen that the adaptation of the invention illustrated in Figure 6 will operate in exactly the same manner as the apparatus shown in Figure 1.

Having thus illustrated my invention and described the same in detail, what I claim as new and desire to secure by Letters Patent is:

1. In a pumping apparatus of the character described, a closed container having a valve controlled inlet opening at the lower end thereof for admitting liquid thereto, a discharge pipe leading from the lower portion of said container, a tube connected to the upper portion of said container, a fluid compressor having an outlet pipe and an inlet pipe connected to said tube, a valve in the outlet pipe, a valve in the inlet pipe, fluid operated means connected to said inlet pipe for opening the valve therein and closing the valve in the inlet pipe, a by-pass line connected to said tube and fluid operated means interposed in said by-pass line for closing the valve in said outlet pipe and operating the valve in said inlet pipe.
2. In a pumping apparatus of the character described, a closed container having an inlet opening at the lower end thereof for admitting liquid thereto, a check valve preventing the flow of liquid from said opening, a discharge pipe leading from the lower portion of said container, a fluid compressor; a tube leading from the discharge end of said compressor to said container,

a pressure tank operatively interposed in said tube, an inlet pipe connecting said tube to the intake of said compressor; a valve in said tube, a valve in said inlet pipe, springs normally holding said valves in a closed position and means operated by fluid pressure for alternately opening said valves.

3. In a pumping apparatus of the character described, a closed container having an inlet opening at the lower end thereof for admitting liquid thereto, a check valve preventing the flow of liquid from said opening, a discharge pipe leading from the lower portion of said container, a fluid compressor; a tube leading from the discharge end of said compressor to said container, a pressure tank operatively interposed in said tube, an inlet pipe connecting said tube to the intake of said compressor; a valve in said tube, a valve in said inlet pipe, springs normally holding said valves in a closed position and means operated by fluid pressure for alternately opening said valves.

4. In a pump of the character described, a closed container having an inlet opening in the lower end portion thereof; a check valve controlling said opening; a discharge pipe leading from the lower portion of said container; a pressure tank, a fluid compressor having an outlet pipe leading to said tank; a tube leading from said tank to the upper portion of said container; a normally closed valve in said tube; an inlet pipe connecting said tube to the intake of said compressor; a normally closed valve in said intake pipe; a lever, yieldable means normally moving said lever to a downward position, means connected to said lever for opening the valve in said tube when the lever is in a downward position; means connected to said lever for opening the valve in said inlet pipe when the lever is in an upward position; a spring operated latch operable to hold said lever in an upward position, regulatable means operated by fluid pressure within said tank for releasing said latch; a by-pass line in said inlet pipe, fluid operated means connected to said by-pass line for moving said lever to an upward position; a manually operated valve at one end of said by-pass line; a normally closed valve at the other end thereof and means operated by a partial upward movement of said lever for opening the last named valve.

LESTER L. CLARK.
